UNITED STATES PATENT OFFICE

HENRY C. SCHRANCK, OF MILWAUKEE, WISCONSIN, ASSIGNOR, BY MESNE ASSIGNMENTS, TO BAKER ICE MACHINE COMPANY, OF OMAHA, NEBRASKA, A CORPORATION OF NEBRASKA

APPARATUS FOR THE MANUFACTURE OF FROZEN CONFECTIONS

Application filed September 19, 1931. Serial No. 563,733.

This invention relates to the manufacture of frozen confections and has as an object to provide a novel apparatus for making the same.

5 Another object of this invention is to provide means for facilitating the filling of paper bags and the like with a liquid.

Another object of this invention is to provide a mold for receiving a paper bag or the 10 like and a form insertable into the mold for facilitating the positioning of a bag therein preparatory to being filled.

Another object of this invention resides in the provision of a form for facilitating the 15 positioning of a bag in a mold which also provides means for receiving the confection to be deposited into the bag, while in a liquid state.

With the above and other objects in view 20 which will appear as the description proceeds, this invention resides in the novel construction, combination and arrangement of parts substantially as hereinafter described and more particularly defined by the appended claims, it being understood that such 25 changes in the precise embodiment of the herein disclosed invention may be made as come within the scope of the claims.

In the accompanying drawing one complete 30 example of the physical embodiment of this invention is illustrated constructed according to the best mode so far devised for the practical application of the principles thereof, and in which:

35 Figure 1 is a perspective view of a complete mold and form for making frozen confections in accordance with this invention;

Figure 2 is a fragmentary detail view of a portion of the form illustrating the manner 40 in which the bags are applied thereto preparatory to being positioned in the molds;

Figure 3 is an enlarged detail section view through the mold with the form and bag inserted therein; and

45 Figure 4 is a detail section view illustrating the confection in the bag with the form withdrawn therefrom.

Referring now more particularly to the 50 accompanying drawing the numeral 5 represents an open topped mold of any desired

size and shape, but preferably having its side walls tapered downwardly. The mold 5 is adapted to receive a paper bag 6 which is of such size that when fully open substantially completely fills the mold with its open 55 top projecting from the open top of the mold as illustrated in Figures 3 and 4.

To facilitate the positioning of the bag 6 into the mold, a form 7 is provided. This form is of such size as to permit its being 60 telescoped into the mold as illustrated in Figure 3, and is adapted to have the bag slipped over its end 8 as illustrated in Figure 2. With the bag thus positioned on the form, the form is telescoped into the mold 65 and serves to hold the bag open.

The form is open from top to bottom and thus permits a frozen confection while in a liquid state, to be poured into the bag 70 through the form, and as it is desirable to measure the quantity of liquid to be poured into the bag, the form 7 has a false bottom 9. The bottom 9 has an opening 10 which communicates with a tube 11 connected at its lower end with the inner end 8 of the form, as at 13, so that the chamber 14 above the false bottom 9 is communicated with the bag interior when the form and bag are in position in the mold.

The capacity of the chamber 14 together 80 with that of the tube 11 is such that when the chamber is filled to the top the desired quantity of liquid confection is received therein. After this quantity of liquid confection has been poured into the form, the form is withdrawn as illustrated in Figure 4, leaving the liquid confection C in the bag.

The mold 5 supports the bag and maintains its shape during the freezing of the confection which is brought about by subjecting the mold with the bag and confection therein to a suitable freezing temperature, and after the confection is frozen the bag may be removed from the mold and its open top folded down, whereupon the frozen confection is 90 ready for sale.

To facilitate manufacture it is desirable to freeze a number of units simultaneously and to this end the molds 5 are supported from a flat plate 15 beneath openings 16 100

therein which register with the open tops of the molds, and the forms 7 are supported from the underside of the bottom 17 of a pan 18. The pan bottom 17 has openings 19 which communicate with the tops of the chambers 14 provided by the upper ends of the forms, and the pan affords a convenient receptacle for the fluid confection during filling of the bags.

10 During the application of the paper bags 6 to the forms, the pan 18 is preferably inverted as shown in Figure 2 and the bags slipped over the ends of the molds which, to prevent tearing of the bags, are rounded.

15 What I claim as my invention is:

1. A bag filling device including a filler form adapted to be inserted into a bag and having a partition forming a measuring chamber therein of smaller capacity than that of the bag and provided with a transfer opening for communicating the chamber with the bag whereby liquid may be transferred from the measuring chamber to the bag when the filler form is withdrawn therefrom.

2. A bag filling device including a filler form adapted to be inserted into a bag and having a partition forming a measuring chamber therein of smaller capacity than that of the bag and provided with a transfer opening for communicating the chamber with the bag whereby liquid may be transferred from the measuring chamber to the bag when the filler form is withdrawn therefrom, and a receptacle for supporting the bag during filling thereof.

3. A bag filling device including a filler form insertable into a bag to be filled, means forming a measuring chamber in the filler form of smaller capacity than the bag and having a throat leading from said chamber through the end of the form whereby liquid may be transferred from the measuring chamber to the bag when the filler form is withdrawn from the bag.

4. A bag filling device including a filler form having a closed end insertable into a bag, means forming a measuring chamber in the filler form of smaller capacity than the bag and having means extending from said chamber through the closed end of the form for transferring liquid from a measuring chamber to the bag when the filler form is withdrawn therefrom.

5. A bag filling device including a hollow filler form having a shape to completely fill the bag to be filled, a partition member extending across the filler form to provide a measuring chamber of less capacity than the bag, a tube in the form arranged for transferring liquid from the measuring chamber to the bag when the filler form is withdrawn therefrom, and means for supporting the bag.

6. A bag filling device including a tray,

a pluraility of hollow filler forms depending from the tray and having a shape to completely fill the bags to be filled, partition members extending across the filler forms to provide measuring chambers of less capacity than the bags and having open communication with the tray, transfer tubes for communicating the measuring chambers with the bags for transferring liquid from the measuring chambers to the bags when the filler forms are withdrawn therefrom, and means for exteriorly supporting the bags during filling thereof.

In testimony whereof I have hereunto affixed my signature.

HENRY C. SCHRANCK.
